Primary Examiner — Kelley A Donnelly(74) *Attorney, Agent, or Firm* — Rumit Ranjit Kanakia(57) **CLAIM**

The ornamental design for a 6-tier kitchen corner shelf, as shown and described.

DESCRIPTION

FIG. 1 is a front elevational view thereof of a 6-tier kitchen corner shelf showing my new design;

FIG. 2 is a rear elevational view thereof; and,

FIG. 3 is a left side view thereof;

FIG. 4 is a right side view thereof;

FIG. 5 is a top plan view thereof;

FIG. 6 is a bottom plan view thereof;

FIG. 7 is a perspective view thereof of a 6-tier kitchen corner shelf showing my new design;

FIG. 8 is a partial enlarged view of FIG. 1; and,

FIG. 9 is a partial enlarged view of FIG. 5.

The broken lines in the figures are for the purposes of illustrating portions of the 6-tier kitchen corner shelf, which form no part of the claimed design.
